CLAIM

The ornamental design for a fryer tray carrier, as shown and described.

DESCRIPTION

FIG. 1 is a rear perspective view of a fryer tray carrier according to my design;

FIG. 2 is a side view of a fryer tray carrier, as shown in FIG. 1, the opposite side view being a mirror image thereof;

FIG. 3 is a frontal view of a fryer tray carrier, as shown in FIG. 1;

FIG. 4 is a bottom view of a fryer tray carrier, as shown in FIG. 1; and,

FIG. 5 is a front perspective view, the broken line showing of a fryer is for illustrative purposes only and forms no part of the claimed design.

1 Claim, 5 Drawing Sheets

FIG. 1

FIG. 2

FIG. 3

FIG. 4

FIG. 5
